GAME BOARD

Sadie Morris, New York, N. Y.

Application January 21, 1948, Serial No. 143,921

Term of patent 7 years

(Cl. D34—5)

To all whom it may concern:

Be it known that I, Sadie Morris, a citizen of the United States and resident of New York, New York, have invented a new, original, and ornamental Design for a Game Board, of which the following is a specification, reference being had to the accompanying drawing, forming part hereof.

The single figure is a top plan view of a game board, showing my new design; the opposite side of the game board is plain and unornamented; the game board is of no appreciable thickness, the markings thereon being surface representations only.

I claim:

The ornamental design for a game board, substantially as shown and described.

SADIE MORRIS.
